(57) **CLAIM**

The ornamental design for a rotatable LED lamp, as shown and described.

DESCRIPTION

FIG. 1 is a front view of a rotatable LED lamp showing our new design with lamp in the planar position;

FIG. 2 is a back view thereof, with lamp in the planar position;

FIG. 3 is a side view thereof, with lamp in the planar position;

FIG. 4 is a top plan view thereof, with lamp in the planar position;

FIG. 5 is a top perspective view thereof, with lamp in the planar position;

FIG. 6 is a bottom plan view thereof;

FIG. 7 is a bottom perspective view thereof;

FIG. 8 is a front view thereof, with lamp in a rotated position;

FIG. 9 is a back view thereof, with lamp in a rotated position;

FIG. 10 is a side view thereof, with lamp in a rotated position;

FIG. 11 is a top plan view thereof, with lamp in the rotated position; and,

FIG. 12 is a top perspective view thereof, with lamp in the rotated position.

The broken line portions shown in the figures are included to show unclaimed subject matter only and form no part of the claimed design.
